UNITED STATES PATENT OFFICE.

WILLIAM J. BRANCH AND EDWARD C. SCHROEDER, OF RICHMOND,
VIRGINIA.

AWNINg.

SPECIFICATION forming part of Letters Patent No. 781,588, dated January 31, 1905.

Application filed August 4, 1904. Serial No. 219,614.

To all whom it may concern:

Be it known that we, WILLIAM J. BRANCH and EDWARD C. SCHROEDER, citizens of the United States, residing at Richmond, in the county of Henrico and State of Virginia, have invented certain new and useful Improvements in Awnings, of which the following is a specification.

This invention provides a novel form of awning-supporting means for doors, windows, or the like, and the essential feature of the invention resides in the provision of means of the class mentioned which is readily detachable in order that the awning may be quickly removed before a storm or for any other purpose and which, further, admits of a disposition of the awning to allow a thorough ventilation at the upper and lower portions of the door or window and admitting light.

The invention obviates the use of ropes or similar devices at present commonly employed in connection with awnings, and the construction of the supporting means is such as to permit detachment of the awning from the side of the building with little or no trouble, the above embodying a special advantageous feature of the invention.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view of the invention applied, parts broken away. Fig. 2 is a vertical sectional view. Fig. 3 is a detail perspective view, parts separated.

Corresponding and like parts are referred to in the following description and indicated in all the views of the drawings by the same reference characters.

In the drawings the awning is represented as being secured to a window, and describing

the supporting means specifically the same consists principally of a transverse supporting-bar 1, attached to the window-frame 2, said frame being of the ordinary form at present in use. The supporting-bar 1 is disposed some distance below the top of the frame 2 and is secured by means of angle-plates 3 50 preferably, said plates 3 being attached to the inner sides of the frame 1 by any suitable fastening means desired. Projected from the bar 1 are the rigid supporting-arms 4, and said arms are laterally spaced and extend outwardly and upwardly from the bar 1, as shown most clearly in the drawings. The inner and lower ends of the arms 4 are detachably secured to the transverse bar 1, and the outer and uppermost ends of said arms carry other 65 supporting-bars 5, to which is secured the awning or canopy proper, 6. The supporting-bars 5 are pivoted to the arms 4, the point of pivotal connection being located approximately and intermediate the ends of said bars 70 5. The awning is secured to the bars 5 by means of fastenings ordinarily employed for this purpose.

The arms 4 are peculiarly mounted upon the supporting-bar 1, the lower ends of said arms being provided with dovetailed extensions 7, which are received in recesses 8 at the ends of the bar 1. The recesses 8 are sufficiently wide to readily receive the extensions 7, and plates 9 are secured to the upper 80 side of the bar 1 adjacent its ends, said plates being slotted and having the slotted portions above the recesses 8. The slot (designated 10) of each plate 9 is narrower than the wider portion of the dovetailed extensions 7, received by the adjacent recess 8, and since the plates 9 terminate some distance from the ends of the bar 1 the extensions 7 are adapted to be readily inserted into the recesses 8 and by a sliding movement disposed beneath 90 the plates 9. Braces 11 are pivoted at their upper ends to the arms 4, and the lower ends of said braces are provided with hooks 12, adapted to engage pins 13, projected upwardly from the bar 1. The braces 11 reinforce the 95 arms 4 when in position, and because of the

interlocking connection of said braces with the bar 1 said arms are rigidly supported in proper positions. The braces 11 are folded against the arms 4 when the awning is removed, so that when the awning-supporting means is "knocked down" the latter will occupy a minimum amount of space. It will be understood that the several members of the supporting means may be made of any suitable material, and either metal, wood, or the like may be utilized for this purpose.

The supporting-bars 5 at the outer ends of the arms 4 are adapted for a pivotal movement, so that said bars may be readily adjusted to dispose the upper portion of the awning spaced from the top of the frame 2, and thereby admit of passage of air and thorough ventilation.

The position of the awning when adjusted as above described will give greater light, though the shade capacity of the awning is not interfered with. The awning having been disposed in position, in order to remove the same the braces 11 are first disengaged from the pins 13, after which the arms may be readily disengaged from the bar 1 and the whole canopy or awning removed.

The dovetailed extension 7 at the lower end of each member 4 is reinforced and protected by means of a plate 18, secured to the inner side of the member 4 at the lower portion thereof, and this plate strengthens the extension 7 at the point of juncture of the same with the member 4, being advantageously used for this reason.

Having thus described the invention, what is claimed as new is—

1. In a collapsible awning-support, the combination of a window-frame, laterally-spaced supporting-arms extended outwardly from said frame, a bar wholly carried by each of said arms and pivoted at a point between its

ends to the respective arm upon which it is mounted, and an awning connecting said bars.

2. In an awning-support, the combination of a window-frame, a transverse supporting-bar on said frame, laterally-spaced supporting-arms detachably mounted upon the supporting-bar at their lower ends and projected outwardly and upwardly from the window, a bar carried by each supporting-arm and pivoted thereto at a point between its ends, an awning connecting the bars aforesaid, and braces holding the supporting-arms in spaced relation. 55

3. In an awning-support, the combination of a window-frame, a transverse supporting-bar attached thereto, outwardly and upwardly extending arms projected from the supporting-bar, an awning carried by the upper ends of said arms, and brace means between the arms and the supporting-bar. 60

4. In an awning-support, the combination of a window-frame, a transverse supporting-bar attached thereto, outwardly and upwardly extending arms projected from the supporting-bar, an awning carried by the upper ends of said arms, and braces pivoted to the arms and coöperating with the supporting-bar. 65

5. In an awning-support, the combination of a window-frame, a transverse supporting-bar attached thereto, outwardly and upwardly extending arms projected from the supporting-bar, an awning carried by the upper ends of said arms, braces pivoted to the arms, and pins projected from the supporting-bar and adapted to be engaged by said braces. 70 75

In testimony whereof we affix our signatures in presence of two witnesses.

WILLIAM J. BRANCH. [L. S.]
EDWARD C. SCHROEDER. [L. S.]
